UNITED STATES PATENT OFFICE.

ANKER PETERSEN, OF WINTHROP, MASSACHUSETTS.

BRAIDING MACHINE.

Application filed September 29, 1923. Serial No. 665,705.

To all whom it may concern:

Be it known that I, ANKER PETERSEN, a citizen of the United States of America, and resident of Winthrop, in the county of 5 Suffolk and State of Massachusetts, have invented new and useful Improvements in Braiding Machines, of which the following is a specification.

This invention pertains to braiding machines of that type in which two series of 10 bobbin carriers are caused to revolve in opposite directions to intertwine their yarns at a centrally disposed braiding point, and relates more particularly to means for driving 15 the bobbin carriers of the inner series.

In my Patent No. 1,413,931 dated April 25, 1922, I have disclosed an arrangement for driving the carriers of the inner series comprising a propelling or pusher roll 20 which is rotated by the frictional engagement of an associated felt roll or washer with a resiliently supported leather ring.

The object of the present invention is to provide improved means for rotating the 25 pusher roll with greater uniformity of action and with substantial freedom from slippage even at extremely high speeds but without sacrificing the simplicity and lightness of weight attainable by the patented 30 structure.

In the accompanying drawings one preferred embodiment of the invention is illustrated by way of example;

Fig. 1 being a fragmentary vertical section through a braiding machine of well 35 known type having the present improvements embodied therein;

Fig. 2 is a plan view of a table or stationary support forming one feature of the 40 invention, and

Fig. 3 is a side elevation to larger scale showing a carrier driving roll together with its actuating pinion and shaft.

Referring to the drawings the frame of 45 the machine is indicated at 1. This frame supports a stationary vertical hollow shaft 2 upon which the sleeve 3 is mounted to turn. The shaft 2 is secured in any suitable manner as by means of a set screw 2^a 50 engaging a threaded opening in the frame and bearing against the shaft.

The lower end of the sleeve 3 is preferably mounted on anti-friction bearings and is furnished with a disk-like plate 4 which 55 is keyed to the sleeve at 5. An annular beveled gear 6 is secured to the beveled edge

of the plate 4 and meshes with a pinion 7 fixed to a main drive shaft 8. The shaft 8 is provided with fast and loose pulleys 9 and 10 respectively and may be driven by a belt from any suitable source of power. 60

A second sleeve 11 surrounds the sleeve 3 about the plate 4, being supported to turn relatively to the sleeve 3 by suitable anti-friction bearings. The sleeve 11 supports 65 a spider 12 which in turn carries an annular beveled gear 13 which also meshes with the pinion 7. The arrangement of the gears 7 and 13 and the pinion 7 is such that the gears turn in opposite directions. 70 The spider 12 is extended outwardly and upwardly to form the outer revolving frame 14 upon which the bobbin carriers (not shown) of the outer series are mounted in the usual manner. 75

An inner, carrier driving frame 15 is keyed to the upper end of the sleeve 3 at the point 15^a. Upon the outer edge of this inner frame a series of brackets 16 is mounted, only one of these brackets being 80 illustrated, it being understood that the other brackets are of substantially the same construction. Each bracket 16 comprises spaced bearings 17 and 18 in which a shaft 19 is mounted. The shaft 19 is substantially radial with respect to the axis of the sleeve 3 and preferably inclines downwardly and outwardly substantially as illustrated. 85

Above the disk 15 an open spider-like frame or table 20 is mounted. This table 90 has a hub 21 which is keyed to the upper end of the stationary shaft 2 at the point 22 and is furnished with an annular guide track 23 upon its upper side and with an annular gear 24 upon its lower side adjacent to its peripheral edge. The outer or peripheral portion of the table 20 is as shown arranged in outwardly diverging relation to the shafts 19 so that at their outer ends these shafts are spaced further from the under side of the table than at their inner ends. 95

The outer revolving frame 14 is furnished in the usual manner with an internal groove 14^a having a substantially flat lower surface 14^b upon which the outer supporting wheels 25 of the bobbin carriers 26 are supported. These bobbin carriers 26 of the inner series are also furnished with supporting wheels or rolls 27 at their inner ends, the latter wheels or rolls resting upon and travelling along the track 23 carried by the table 20. 100 105 110

A pusher-roll 28 is secured to the outer end of the shaft 19 of each of the brackets 16. The shafts 19 project outwardly beyond the edge of the table 20 which overlies the brackets 16 and the rolls 28 are of a diameter such that they project upwardly beyond the edge of the table. These rolls are preferably formed of felt or some similar material and engage rolls 29 carried by the respective bobbin carriers 26.

A pinion 30 is associated with the pusher-roll 28 of bracket 16, being connected to the roll in any desired manner to rotate therewith. Pinions 30 are of smaller diameter than the rolls 28 and mesh with the gear 24 on the under side of the table 20.

When the main drive shaft 8 is rotated the sleeves 3 and 11 turn in opposite directions, thus causing the outer frame 14 to turn oppositely to the inner frame 15 upon which the brackets 16 are mounted. The carriers 26 of the inner series are free to travel along the concentric tracks 14^b and 23 and as the inner frame 15 rotates the pusher rolls 28 propel the carriers in a circular path around the axis of the machine.

In order to avoid undue friction upon the yarn of the outer series of carriers which must necessarily pass between the rolls 28 and 29, it is desirable to rotate the rolls 28 and for best results to rotate such rolls in a positive manner. This is accomplished in the present machine by the gear and pinion drive, comprising the parts 24 and 30, which compels the pusher rolls 28 to rotate at a speed exactly in accordance with the speed at which the inner frame is driven. Slippage between the surfaces of the pusher roll 28 and the roll 29 is thus reduced to a minimum with consequent gain in efficiency and substantial elimination of yarn breakage.

The desired result is thus attained without substantially complicating the mechanism and without unduly increasing the weight of the parts which is highly important in 45 machines of this character which are commonly run at speeds of the order of 3000 R. P. M.

I claim:

A braiding machine comprising an outer frame provided with an annular carrier supporting track, an inner frame, means for turning said frames in opposite directions about a common axis, a fixed disc-like table overlying the inner frame and having an 55 annular carrier supporting track concentric with the track of the other frame, a carrier having anti-friction means engaging the respective tracks, a rotary shaft below the table, said shaft being supported by the inner 60 rotating frame and extending radially outward and downward with its axis intersecting the plane of the table substantially at the center of the latter, a pusher-roll mounted upon the shaft adjacent to the outer end 65 of the latter and engageable with an element of the carrier to propel it along its supporting tracks, a pinion co-axial with the pusher-roll and disposed closely adjacent to the inner side of the latter and connected to the 70 pusher-roll, the pinion being less in diameter than the roll and underlying the peripheral edge portion of the table, and an annular gear secured to the under side of the table and meshing with the pinion whereby to 75 rotate the latter and the pusher-roll about the axis of the pusher-roll shaft when the inner frame turns relatively to the table.

Signed by me at Boston, Massachusetts, this 26th day of September, 1923.

ANKER PETERSEN.
